UNITED STATES PATENT OFFICE.

LAURENCE H. POMEROY, OF CLEVELAND, OHIO.

DESIGN FOR A COMBINED AUTOMOBILE HOOD AND RADIATOR.

57,722.

Specification for Design.

Patented Apr. 26, 1921.

Application filed April 9, 1920. Serial No. 372,680. Term of patent 14 years.

To all whom it may concern:

Be it known that I, LAURENCE H. POMEROY, a subject of Great Britain, residing at Cleveland, in the county of Cuyahoga and State of Ohio, have invented a new, original, and ornamental Design for a Combined Automobile Hood and Radiator, of which the following is a specification, reference being had to the accompanying drawing, forming part thereof.

Figures 1, 2 and 3 of said drawings are

a side elevation, front elevation and plan, respectively, of a combined automobile hood and radiator showing my new design, the main outlines of body and running gear parts being shown in broken lines. The surfaces at *a* and *b* are convex, those at *c*, *c* are concave, and those at *d*, *d* are plane.

I claim:

The ornamental design for a combined automobile hood and radiator, as shown.

LAURENCE H. POMEROY.
